UNITED STATES PATENT OFFICE.

JOSEPH McCARTHY, OF FRANKLIN, OHIO, ASSIGNOR OF THREE-FOURTHS TO LEO H. McCARTHY, OF SAME PLACE, AND CHAS. B. OGLESBY, OF MIDDLETON, OHIO.

WATCHMAN'S TIME-DETECTOR.

SPECIFICATION forming part of Letters Patent No. 610,145, dated August 30, 1898.

Application filed June 13, 1898. Serial No. 683,266. (No model.)

To all whom it may concern:

Be it known that I, JOSEPH McCARTHY, a citizen of the United States, residing at Franklin, in the county of Warren and State of Ohio, have invented certain new and useful Improvements in Watchmen's Time-Detectors; and I do hereby declare that the following is a full, clear, and exact description of the invention, which will enable others skilled in the art 5 to which it appertains to make and use the same, reference being had to the accompanying drawings, and to the letters of reference marked thereon, which form a part of this specification.

This invention relates to new and useful improvements in time-detectors for night watchmen.

The invention has for its object the provision of a cheap instrument for the purpose of ascertaining whether a watchman is attending 20 to his duties.

In the accompanying drawings, Figure 1 is an elevation of a portion of the inner side of a door to which a portion of the time-detector is attached. The clock and its supporting-case are detached. Fig. 2 is an elevation of the opposite side of the supporting-plate shown in Fig. 1. Fig. 3 is a section on the line $x-x$ of Fig. 1, with the clock and its supporting-case in position. Fig. 4 is an elevation of the clock-supporting case detached. Fig. 5 is an elevation of the time dial or disk.

Similar letters of reference indicate corresponding parts in the several views of the drawings.

The drawings show my improved time-detector attached to the inner side of a door A, and for which purpose there is a suitable recess B therein. A lock C is secured in said 35 chamber. This lock has a key-opening entirely through it, so that when a half-turn is given the key D it will be in a position to be passed entirely through the lock, as shown in Fig. 3.

A supporting-plate E is secured to the inner side of the door, over the recess therein, and has mounted on its inner side a resilient arm K, that is movable inwardly and also in

an arc of a circle. The inward movement is had by the front lug or ward e of the key 50 coming in contact with the upper part thereof, and the arc movement is had by means of a segment-gear L, which is fixed to the shaft upon which said arm is also fixed. A pinion M meshes with said segment-gear and is 55 turned by a finger-piece O, that is on the inner end of the shaft upon which the said pinion is mounted. A plate N also turns with the said shaft and has on it an index-mark a, that may be brought in line with any of the 60 marks b on the rear side of the plate E, which indicate the days of the week and correspond with the concentric spaces on the time-dial I. This enables the arm K to be moved to bring the pin J thereon in a position to make contact with the dial in the proper space. The supporting-plate E has a T-shaped slot F and a segmental slot F'.

The time-dial, as before stated, has a series of concentric spaces. These spaces designate 70 the several days of the week; but the innermost one contains the time, and the said dial moves with the center pinion of the clock in a well-known manner. It is accessible to the pin J through the segmental slots F' and H, 75 the latter slot being in the wall of the clock-supporting case G. The back of this case G is open, so the clock P may be placed therein. The said case G is supported on the plate E by means of a T-shaped projection F'', which 80 locks with the T-shaped slot F in the plate E. The clock and its supporting-case G may be easily detached from this position each morning, examined, and placed away by the person opening the store or other place where 85 the time-detector is used. When the said case G is in position on the plate E, the segmental slot H becomes in line with the similar slot in the plate E, so that the pin J may pass through said slots at any point of their 90 length.

The lock C may be of any of the well-known types that have keys with special wards, and an opening is provided therein for the key to pass entirely through it, as shown in Fig. 3. 95 When the key is moved to a position to admit

of its being thus pushed entirely through the lock, the front lug or ward *e* will come in contact with the end of the arm *K*, and the pin *J* on said arm will be pressed in against the 5 dial *I*. The said arm *K* is set with relation to the concentric spaces on the dial by turning the finger-piece *O* until the index-point *a* comes in line with the proper day on the adjacent scale.

10 The device, it will be observed, is non-accessible at all times to the watchman, save through the use of a key with which he is provided for the purpose of registering his presence.

15 Having described my invention, I claim—

1. In a watchman's time-detector, the combination of a clock having a rotating time-dial, and a lock having a key-opening entirely through it, of a resilient arm mounted between 20 the lock and the face of the dial and movable in an arc, a pin on said arm that may be shifted to vary the positions of its impressions on the time-dial when the key is moved inwardly against said arm, substantially as and 25 for the purposes specified.

2. In a watchman's time-detector, the combination of a supporting-plate having a T-shaped and a segmental slot therein, a clock-supporting case having a T-shaped projection 30 adapted to interlock with the T-shaped slot in said supporting-plate, and a segmental slot in said clock-supporting case, a resilient arm with pin thereon adapted to project through said segmental slots, a segment-gear fixed to 35 the shaft of said arm, and a pinion meshing with said segment-gear, and means for directing the movement of said pinion to regu-

late the position of the said arm, substantially as and for the purposes specified.

3. In a watchman's time-detector, the combination of a supporting-plate having a T-shaped and a segmental slot therein, a clock-supporting case having a T-shaped projection adapted to lock with said T-shaped slot, and a segmental slot adapted to be in line with 45 the segmental slot in the supporting-plate, a time-dial exposed through said segmental slots, a segment-gear connected with said arm, a pinion meshing with said segment-gear, and a lock and key by means of which 50 said resilient arm is operated, substantially as and for the purposes specified.

4. In a watchman's time-detector, the combination of a supporting-plate having a segmental slot therein, a clock-supporting case 55 mounted on said supporting-plate and having a segmental slot therein in line with the similar slot in the said supporting-plate, a time-dial exposed through said segmental slots, a resilient arm mounted on said supporting-plate, a pin on said arm adapted to puncture the dial through the said segmental slots, a segment-gear connected with said arm, a pinion meshing with said gear, and a scale and pointer for directing the movement 60 of said arm and pin through said gearing, substantially as and for the purposes specified.

In testimony that I claim the foregoing as my own I hereto affix my signature in presence of two witnesses.

JOSEPH McCARTHY.
